W. H. MCKISSICK.
OIL WELL APPARATUS.
FILED JAN. 15, 1921.

UNITED STATES PATENT OFFICE.

WILLIAM H. MCKISSICK, OF TULSA, OKLAHOMA.

OIL-WELL APPARATUS.

Application filed January 15, 1921. Serial No. 437,431.

To all whom it may concern:

Be it known that I, WILLIAM H. MCKISSICK, a citizen of the United States, residing at Tulsa, in the county of Tulsa and State of Oklahoma, have invented new and useful Improvements in Oil-Well Apparatus, of which the following is a specification.

This invention relates to oil well apparatus, and particularly to a means whereby the pump tubing may be drained of any oil within the same before the pump tubing is lifted to the surface of the ground for repairs, or for other purposes. In the operation of deep wells, the oil, water, or gas is ordinarily brought to the surface by means of a pump carried by a string of tubing, through which the oil, or fluid, is conveyed from the bottom of the well to the surface of the ground. According to the standard practice, the lower end of this string of tubing, or pump tubing, as it is sometimes called, is provided with an upwardly opening check valve, known as a standing valve. This standing valve traps the oil, or fluid, in the string of tubing, with the result that when it becomes necessary to pull the tubing from the well for the purpose of making some adjustments, or repairs, as has been stated, the oil, or fluid, which is trapped in the string of tubing, in the standing valve, is lost. Ordinarily, several barrels of oil are wasted in this manner as the tubing string is withdrawn. This entails a considerable loss. The object of this invention is to provide a novel and effective means for opening this valve and permitting the oil in the string of tubing to drain back into the well before the tubing is withdrawn, thereby saving the oil and facilitating the withdrawal of the tubing from the well, since this trapped oil in the tubing adds materially to the weight thereof, and makes the handling of the tubing more difficult.

In practicing the invention, I provided a standing valve having a cage, or yoke portion attached thereto, and above said valve. The opening in said valve is ordinarily closed by means of a ball. A stem, provided with a curved foot, has its stem portion extending through a bearing in the yoke member. Resilient means are interposed between a head on the end of said stem, and the top of the yoke. Said resilient means tends to at all times prevent the curved foot from contacting with the ball in the valve opening. If it is desired to drain the tubing of

oil, weights would be dropped through said tubing after the sucker rods had been withdrawn from the same, so that they may contact with the head of the stem, depressing 60 said stem, and causing the curved foot to engage a side of the ball and unseat the same from the valve opening. This, of course, permits the oil to pass through the valve opening, and into the casing. 65

Further objects of the invention are to provide a device for opening a standing valve of a string of tubing, which can be used with standard oil well equipment, without the necessity of any material changes there- 70 in, which is entirely dependent in its action, and which has no complicated parts to break or get out of order.

With these and other objects in view, the invention consists of novel combinations, arrangements and associations of the parts, as will more fully appear as the description proceeds, the novel features thereof being pointed out in the appended claims. 75

Referring to the drawing, Figure 1, is a 80 fragmentary cross-sectional elevation of the improved means for draining a string of tubing, and showing the ball seated over the valve opening;

Figure 2 is a view similar to Figure 1, 85 but showing the ball unseated from the valve opening, resultant upon pressure being exerted downwardly upon a stem member; and

Figure 3 is a cross-sectional view taken on the line 3-3 in Figure 1, and looking in 90 the direction of the appended arrows.

Corresponding parts in all the figures are designated by the same reference characters.

Referring with particularity to the drawing, A designates a well casing, B a string 95 of tubing, commonly called pump tubing, and C a valve, or valve operating device, associated with said string of tubing, all of which elements are used in practicing one embodiment of the invention. 100

It will be understood that a pump of any standard construction is fitted to the tubing above the valve and valve operating mechanism C, and that the fluid will be pumped to the surface of the well through the tubing. 105

The improved device C may include a valve 1 held to the lower end of the string of tubing B, as shown at 2, by means of a sleeve or coupling 3, having a screw threaded engagement with the string of tubing B. 110 Said sleeve 3 is provided with an internal annular shoulder 4, which shoulder has its

inner peripheral surface 5 convergently angled downwardly, as shown at 6. The device C is seated within the string of tubing B, as has been stated. The shoulder 4 aids in retaining the lower cone shaped body portion of the valve 1 in position, as shown. The valve 1 is provided with a longitudinal bore 7 extending therethrough, and the top portion of said bore 7 is normally closed by 10 means of a ball member 8 seated therein. Yoke members 9 and 10 rise from the surface 11 of the valve body 1, said yoke members being at right angles to each other as shown. Any number of yoke members 9 and 10 may 15 be provided. The apex of where the two yoke members 9 and 10 meet is provided with a bearing 12. A stem member 13 extends through said bearing 12. One end of said stem, as at 14, is provided with a curved 20 foot 15, while the opposite end of the stem, as at 16, is provided with a head 17. Said curved foot 15 may be detachably joined with the stem by means of bolts or screws, as shown at 18. The curved foot 15 is provided with a bearing end 19, to prevent excessive wear on the same when the device C is operated. The valve stem is resiliently urged upward by means of a coil spring 20 interposed between the head 17 and the apex 30 21 of the yoke members 9 and 10, with the said spring 20 encircling the stem 13.

If it were desired to drain the tubing of oil, the sucker rods would first be withdrawn from said string of tubing, and 35 weight members W would be dropped through said tubing so that they might contact with the head 17, as shown at 22, and depress the spring 20, causing the curved foot 15, and particularly the portion 19, 40 to engage with the ball 8 and unseat the same from the valve seat, as shown at 23. When this occurs, it is, of course, obvious that any oil within the tubing would drain through the opening 7 into the space 45 confined by the casing A. The number of weights W required to exert pressure on the head 17 is immaterial, as it is only necessary to drop a sufficient number, according to

the depth of the well, and the weight of the fluid that it is necessary to drain back into 50 the well to properly depress the stem.

While I have illustrated and described one particular embodiment of my invention, it will be understood that I do not restrict myself to the exact details shown, since it 55 will be obvious that numerous modifications and changes can be made without in any manner departing from the spirit of the invention.

Having thus disclosed my invention, I 60 claim and desire to secure by Letters Patent:

1. The combination with a string of tubing having a standing valve at its lower end and wherein a pump piston is adapted to be reciprocated by a string of sucker rods thereby to elevate liquid through the tubing in accordance with standard practice, of a device situated adjacent the standing valve for unseating the same, and means adapted to be dropped into the tubing upon the withdrawal therefrom of the pump piston for actuating said device and unseating the standing valve so that the quantity of the aforesaid liquid that is then within the tubing may drain back into the well preparatory to pulling the tubing.

2. The combination with a string of tubing wherein a pump piston is adapted to be reciprocated by a string of sucker rods thereby to elevate liquid through the tubing 80 in accordance with standard practice, of a drain valve for said tubing, and means adapted to be lowered into the tubing upon the withdrawal therefrom of the pump piston for opening the drain valve so that liquid within the tubing may drain back into the well preparatory to pulling the tubing.

In testimony whereof, I have signed my name to this specification in the presence of 90 two subscribing witnesses.

WILLIAM H. McKISSICK.
